(57) **CLAIM**

We claim the ornamental design for a sensor housing for a side-view mirror of an automated vehicle, as shown and described.

DESCRIPTION

FIG. 1 is a perspective view of showing our new sensor housing design adjacent to a side-view mirror of a vehicle; FIG. 2 is a perspective view of the housing; FIG. 3 is a front view of the housing; FIG. 4 is a side view of the housing; FIG. 5 is a rear view of the housing; FIG. 6 is a top view of the housing; and, FIG. 7 is a bottom view of the housing. The environment illustrated in broken dash line in FIGS. 1-7 form no part of the claimed design.
